UNITED STATES PATENT OFFICE.

EDWARD D. CONKLIN, OF MADISON, NEW JERSEY, ASSIGNOR TO THE WHITEHEAD & HOAG COMPANY, OF NEWARK, NEW JERSEY, A CORPORATION OF NEW JERSEY.

BUTTON PENCIL OR PEN HOLDER.

1,183,436.

Specification of Letters Patent. Patented May 16, 1916.

Application filed November 6, 1915. Serial No. 60,159.

To all whom it may concern:

Be it known that I, EDWARD D. CONKLIN, a citizen of the United States, and resident of Madison, in the county of Morris, in the 5 State of New Jersey, have invented new and useful Improvements in Button Pencil or Pen Holders, of which the following, taken in connection with the accompanying drawings, is a full, clear, and exact description.

10 This invention relates to certain improvements in button pencil or pen holders.

The primary object of the invention is to provide an efficient, simple and economically manufactured pencil or pen holder embodying a button adapted to display insignia, advertising, and like matter.

Other objects will appear from the following description, taken in connection with the accompanying drawings, in which—

20 Figure 1 is a perspective view of the device. Fig. 2 is a longitudinal cross section of the device showing a portion of a garment positioned between a portion of the device and a pencil indicated in dotted lines.

25 Fig. 3 is a central lateral section of the device. Fig. 4 is a view of the portion of the blank from which the hollow ball at the end of the spring arm is formed. Fig. 5 is a plan view of a modified form of holder.

30 Fig. 6 is a cross section on line 6—6, Fig. 5. Fig. 7 is a cross section similar to Fig. 6, of another modified form of holder. Fig. 8 is a cross section similar to Fig. 6, of a still further modified form of holder.

35 The invention comprises a thin elongated sheet metal member comprising a base —1— and a spring tongue —2—, the base having resilient pencil clasping jaws —3— formed by bending side portions thereof in arcuate 40 form. The spring tongue —2— is formed slightly concave longitudinally and terminates in a holding ball —4— formed by bending into substantial contact the projecting portions —5— at the end of the 45 blank from which the spring tongue is formed.

The body —1— is provided with a longitudinal slot —6— through which lugs —7—, struck up from a flanged disk —8—, extend 50 and these lugs are bent into contact with the adjacent depressed portions —7'— of the body —1— to firmly secure the body —1— to the flanged disk —8—. The portions —7'— are, in this instance, depressed a distance substantially equal to the thickness of

the metal forming disk —8—, so that in the assembled structure the surfaces of lugs —7— lie in planes coincident with the interior surface of member —1— to form a smooth, unobstructed, interior passage for 60 the pencil or pen. The disk —8— is provided with a flaring flange —9— within which is seated a disk or pad —10— of suitable material such as cardboard.

A second sheet metal disk —11— is provided and has a covering —12— of suitable material, such as celluloid, for carrying or displaying insignia, advertising, or other matter. This disk —11— is provided with a circumferential flange —13— adapted to 65 telescope with and outside of the flaring flange —9— upon disk —8— and to be bent into frictional engagement therewith to firmly interlock the parts, and preferably the covering —12— of celluloid is of some- 70 what greater extent than the disk —11— and has its marginal portion extending around the flange —12— so as to lie between the flanges —9— and —13— in assembled 75 condition of the structure.

The spring tongue —2— preferably comprises an offset portion —14— of substantially the same lateral extent as the amount of projection of the ball —4— laterally of the spring tongue —2—, so that the surface 80 of the ball will normally lie in substantial contact with a pencil engaged between the jaws —3— and may be sprung outwardly to allow the insertion of a portion of a garment, as —15—, between the pencil and the 85 ball.

In Figs. 5 and 6, a reversal of the structure of the former figures is disclosed in that the lugs —7— are formed by pressing out a portion of the base —1—, and the disk —8— is provided with a pair of spaced 90 openings —16— through which the lugs —7— are passed and then pressed into contact with the inner face of the disk —8—.

In Fig. 7, the base —1— and disk —8— are provided with registering openings —17— and —18— through which an eyelet —19— is passed, the opposite edge portions of the eyelet riveted into contact with the inner face of the disk —8— and the outer 100 face of the base —1—, respectively. Preferably the disk —8— is provided with a depressed portion —20— adapted to receive a projecting portion —21— formed upon the base —1— for preventing any relative 105 110

rotary movement of the parts about the connecting eyelet —19—, and preferably I provide a sheet metal plate —22— of proper conformation to fit against the inner face of the disk —8— and across the eyelet —19—.

5 In Fig. 8, the eyelet is formed by pressing out a portion of the disk —8—, the eyelet —19— extending through an opening —23— in the base —1— and riveted or clenched 10 into contact with the outer side of said base to firmly connect the parts.

In each of the constructions the disk —8— 15 as an advertising button is permanently and rigidly secured to the base —1— of a pen or pencil holder having the curved clasping jaws —3—, the spring arm —2— offset from the plane of the base —1— and provided with a formed head —4—, the offset of said 20 spring arm tending to compensate for the lateral extension of said head to allow the efficient securement of the holder to a garment or like article.

Although I have shown and described one 25 particular form and construction of device and certain variations and modifications thereof, I do not desire to limit myself to the same, as changes may be made in the details of both form and construction without departing from the spirit of this invention 30 as set forth in the appended claims.

What I claim is:—

1. In a device of the class described, a disk and a base, one of said members provided with a pair of openings, the other

member provided with a pair of integral 35 flanges passed through said openings and clenched into engagement with the other member, curved receiving jaws on said base, and a spring arm extending from the base and terminating in a gripping head. 40

2. In a device of the class described, a pair of spaced interengaged disks, one of the same provided with spaced openings, a base provided with spaced integral flanges passed 45 respectively through said openings and clenched into contact with the inner face of said disk, a pair of coacting curved jaws on said base, and a spring arm extending from the base and terminating in a gripping head.

3. In a button pencil holder, a spring arm 50 terminating in a plurality of flanges, said flanges bent into contact upon one side of said arm to form a substantially closed hollow head.

4. In a button pencil holder, a spring arm 55 terminating in three flanges, two of said flanges projecting from opposite sides of the arm and the third flange projecting from the end of the arm, said flanges bent into contact to form a substantially closed hollow ball projecting from one side of the arm. 60

In witness whereof I have hereunto set my hand this 20th day of October, 1915.

EDWARD D. CONKLIN.
